UNITED STATES PATENT OFFICE.

DAVID R. STEDMAN, OF ELIZABETH, NEW JERSEY, ASSIGNOR OF ONE-HALF
TO GEORGE H. HORNING, OF SAME PLACE.

PERMUTATION-LOCK.

SPECIFICATION forming part of Letters Patent No. 298,810, dated February 19, 1884.

Application filed June 19, 1883. (Model.)

To all whom it may concern:

Be it known that I, DAVID R. STEDMAN, a citizen of the United States, and a resident of Elizabeth, in the county of Union and State of New Jersey, have invented certain new and useful Improvements in Permutation-Locks, of which the following is a specification.

The main object of my invention is to produce a permutation-lock which shall be composed of a reduced number of parts, and be compact, simple, and cheap in its construction, and therefore especially adapted to certain articles and structures to which the application of this class of locks has heretofore been impracticable or objectionable, owing to the comparatively large amount of space occupied by the locks and expense involved in their construction.

The improvements claimed herein lie chiefly in the mechanism for operating or throwing the bolt of the lock; and their principal features consist, first, in the combination, with the bolt-operating lever or levers and a cam for actuating the same, and arranged to operate independently of the tumbler mechanism, of a yielding connection between said lever or levers and the cam; and, second, in the arrangement of the cam with relation to its handle and the connection of said handle with the cam-spindle.

The said improvements further consist in the combination of certain details of construction, which, together with the principal features, will be specifically described and claimed hereinafter.

In the accompanying drawings, Figure 1 is a rear elevation of a lock embodying my improvements; and Fig. 2 is a vertical transverse section taken on the line $x-x$ of Fig. 1, showing the lock applied to the hasp of a trunk.

Referring to the drawings, d d' d'' represent the tumblers of the lock, and they are provided with notches extending from their peripheries radially inward, as shown. These tumblers are each preferably formed integral, or of one piece or plate of metal, and are provided with the usual colliding-pins, as shown.

These pins may preferably be permanently fixed to the tumblers at suitable points by being screwed in the same or riveted thereto. The tumblers are mounted loosely upon the

stud c , so that they may rotate freely thereon, and they are separated and held at proper distances apart by stationary washers, as usual. I prefer to provide the tumbler d with a toothed periphery, which engages with the correspondingly-toothed periphery of a driving-wheel, f . The dial E , provided with the usual numbers or other characters, is united to the driving-wheel f , and therefore the motion imparted to the dial by the hand will be conveyed to the tumblers by the driving-wheel f through its geared connection with them, as will be readily understood. The general manner in which the notches in the tumblers are brought abreast or opposite to each other to allow the bolt to be retracted, as well as the arrangement of the tumblers themselves, is well known, and therefore a detailed description of the same will be unnecessary. I prefer to set or change the combination of dial-characters which are used to govern the movement of the dial in manipulating the tumblers by means of an adjustable connection between the spindle F and the driving-wheel f , as will now be described. The spindle F is at one end secured rigidly to the dial, and at its other extremity is formed into a cylindrical stem of smaller diameter than the main portion of the spindle, as shown in Fig. 2. This stem extends through a circular aperture in the center of the wheel f , and is screw-threaded and fitted with a nut, n , as shown. By means of this nut the wheel f may be tightly clamped against the shoulder e of the spindle F , as will be readily understood. When, therefore, it is desired to set or change the combination of dial-characters, the dial is first turned to the left until all of the pins upon the tumblers collide with one another. The dial is arrested when the notch in tumbler d' gets in line with the bolt; and the tumblers then being allowed to remain at rest, the dial-spindle F is detached from its rigid connection with the driving-wheel f by loosening the nut n . The dial and its spindle being now free to turn independently, they are revolved alone until the character which has been selected as the initial character of the combination appears opposite the index, when the movement of the dial is again arrested, the nut screwed down, and the driving-wheel f again rigidly secured to the spindle F . The

dial and driving-wheel are now turned to the right until the pins between tumblers d and d' collide, and the notch in tumbler d' appears in line with the bolt, when the dial is arrested, 5 and the character then appearing opposite the index is noted as the second character of the new combination. The motion of the dial is now reversed to the left, and is arrested when the notch in the geared tumbler d is in alignment with the bolt, when the character on the dial opposite the index is noted as the final character of the combination. The notches in the tumblers will now all be in line with the bolt, and in proper position to allow the latter 10 to be retracted. The tumblers may thereafter be similarly arranged under the new combination by manipulating the dial in the usual manner, as will be readily understood. It will therefore be seen that all of the numbers or 15 characters of the combination succeeding the first or initial character are determined by the positions of the tumblers, instead of being predetermined, and the positions of the parts of the lock made to conform to the entire prearranged formula; but the initial character of 20 combinations set according to the construction described may, however, be predetermined, as will be readily understood.

By means of the arrangement for and method of setting or changing the combination of dial-characters which I prefer to employ, and which has just been described, a very simple construction of tumblers may be made use of, as it is unnecessary that any portion of the 25 latter should be movable or that movable pins be employed. This arrangement therefore conduces materially to the general simplicity of the lock. The stud c , upon which the tumblers are mounted, is rigidly attached to the 30 plate B, preferably by being screwed therein, as shown in Fig. 2. This plate is riveted to the side of the larger face-plate, A, and through both of these plates the dial-spindle F extends, as shown. Two elongated lugs or projections, 35 i , are formed upon the side of the plate B. Within holes formed laterally through these projections a bolt, h , (shown partly in full and partly in dotted lines in Fig. 1 and in dotted cross-section in Fig. 2,) is arranged to horizontally slide. This bolt is preferably of oblong cylindrical form, and is mounted so as to directly enter the slots in the tumblers when they are all abreast of each other and in line with the bolt, as will be readily understood 40 upon reference to Fig. 1, the notches being of equal or preferably slightly greater width than the diameter of the bolt. As will be seen, however, the bolt will be prevented from retracting and be locked when one or more of 45 the tumblers are turned away from the bolt—as, for instance, in Fig. 1.

The bolt operating or throwing mechanism, which forms the principal portion of the subject-matter hereinafter claimed, will now be 50 described. Two links or levers, l L, are respectively pivoted to the right-hand extremity m' of the bolt h and to the plate B at p , and

they are pivoted together at their opposite extremities, m , to form an elbow or toggle joint, as shown, and are so arranged that the line of longitudinal motion of the link l will be nearly coincident with the line of motion of the bolt h , as will be apparent upon reference to Fig. 1. A flat spring, o , is rigidly attached at one end to the side of the lever L near its junction with the lever l , the other end of the spring being free and projecting away from said lever, as shown, and into the path of a rotating cam, M, which is mounted upon a spindle rotating in and extending through the plates A and B, 70 and therefore the cam operates independently of the dial-spindle or tumbler mechanism. It will therefore be seen that when the tumblers are arranged by the dial with their notches abreast of each other and in line with the bolt h 75 the latter may be retracted into the notches by turning the cam in the direction of the arrow, when the spring o will force the levers L and l , and consequently the bolt h , to the right, the bolt being caused to enter the notches in 80 the tumblers, as will be readily understood. The turning of the cam should be continued until its extremity is forced past the end of the spring o , when the cam may be allowed to rest (by virtue of the gravity of its operating pendent ring K, hereinafter described) 85 against the opposite side of the spring o . The bolt may then be thrown back to its locked position by turning the cam in the opposite direction, when the latter will engage with the 90 opposite side of the spring o and force the same to the right, as will be understood. The spring o should, however, be sufficiently stiff to prevent the cam, when moving in the direction of the arrow, from slipping past its 95 extremity when the notches in the tumblers are in line with the bolt until the bolt has been fully retracted.

It will be seen that by means of the yielding connection between the levers L and l and the cam M (which connection is formed by the spring o) the cam may be very easily placed in position for throwing the bolt back to its locked position after the same has been retracted by the cam, and also that, should the 100 cam be accidentally or inadvertently turned while the bolt is locked with considerable force in the direction of the arrow, undue or harmful pressure upon the peripheries of the tumblers by the end of the bolt in its effort 105 to retract will be prevented by the yielding connection between the cam and the bolt-operating levers, since the spring o bends sufficiently in the direction of the rotation of the cam (the levers L and l remaining rigid,) to allow the cam to pass its extremity, and compensates the force upon the bolt. Consequently but little force from the cam is 110 communicated to the bolt under such conditions. This connection, therefore, constitutes an important feature of my invention.

While I have shown two levers or links for throwing the bolt h , it is obvious that one may be dispensed with (preferably the lever l) and

the lever L alone be used in connection with the spring o and cam M and be directly united with the bolt, as will be readily understood; but I greatly prefer to employ the toggle-jointed form of levers which I have described, since by their use a very easy motion is given to the bolt by reason of the great amount of leverage obtained, and this motion is made very certain, owing to the motion of the lever 10 l being nearly coincident with the bolt.

In the drawings I have shown the bolting mechanism as applied to the body and hasp of a trunk, and this application is more fully illustrated in Fig. 2.

15 The plate B, upon which the parts of the lock are mounted, is adapted to be set into an aperture in the side of the trunk, as shown in Fig. 2, and it may be secured to the trunk by screws passing through the face-plate A into 20 the body of the trunk.

The hasp v may be hinged to the lid of the trunk, as usual, and is provided with a lateral yoke, b. This yoke is adapted to be inserted through the aperture a in the plates A and B, 25 and may be locked to the plates by the bolt h, as shown in Fig. 1 and in dotted lines in Fig. 2.

The yoke will be unlocked and be free to be withdrawn, and the trunk may be opened when the bolt is retracted into the slots in the 30 tumblers, as will be readily understood.

The mechanism may be protected and inclosed by a suitable cover, one serving this purpose being illustrated in Fig. 2. This cover should preferably be removably attached to 35 the lock, so that access may be had to the mechanism of the latter.

I prefer to construct the dial A of a flat form, as shown in Fig. 2, and it may, as also the outwardly-projecting portion of the spindle, to which the cam M is attached, be provided with a ring-handle, K. These rings 40 may be loosely mounted upon the outer portions of the dial and cam-spindles, as shown, and they will therefore normally hang by 45 gravity parallel with the side of the trunk.

The portion of the ring-handle K of the cam which depends below the axis of the spindle to which said handle is attached should 50 preferably be of sufficient weight to overbalance the cam, so as to normally maintain the latter in contact with the spring o by its own weight, as shown in Fig. 1. The whole outer arrangement of the lock is thus compact, strong, and simple, and well adapted to withstand

all usages to which trunks are ordinarily subjected. 55

It may be observed that while my invention is particularly adapted to and designed for trunks and similar articles, as above described, it may also be applied by obvious modifications to other articles, and to the doors of safes or other structures. 60

I claim herein as my invention—

1. In a permutation-lock, a bolt having its actuating or throwing lever or levers operatively united with a cam operating independently of the dial or tumbler mechanism, in combination with a yielding connection between said lever or levers and cam, whereby the force of the cam is compensated, substantially as herein set forth. 7c

2. In a permutation-lock, the combination of a series of notched tumblers, a bolt, one or more levers for moving or throwing said bolt, the cam M, and the spring o, united to said lever or levers at one extremity, and having a free end projecting in the path of said cam, substantially as and for the purpose set forth. 75

3. In a permutation-lock, the combination, with the lever mechanism for throwing the bolt, of a cam, for operating said mechanism, and a pendent handle attached to the spindle of the cam, and so arranged that a sufficient amount of its weight to overbalance the cam will normally hang below the axis of said spindle, substantially as herein set forth, whereby the cam may be normally maintained in engagement with said lever mechanism, substantially as herein shown and described. 85

4. In a permutation-lock, the combination, 90 with the plate B, having projections i i, of the series of notched tumblers, the bolt h, mounted in or upon said projections, the lever l, pivoted to said bolt at one extremity, the lever L, pivoted to said plate at one end and pivoted to the lever l at its other extremity to form a toggle-joint, the cam M, and the spring o, 95 united at one end to the lever L, and having its free end projecting in the path of said cam, substantially as herein set forth. 100

In testimony whereof I have hereunto set my hand this 16th day of June, A. D. 1883.

DAVID R. STEDMAN.
